(57) **CLAIM**

The ornamental design for a tractor accessory step extension, as shown.

DESCRIPTION

FIG. 1 is a rear isometric view of the best mode of my tractor accessory step extension;

FIG. 2 is a left side isometric view thereof;

FIG. 3 is a frontal, bottom isometric view thereof;

FIG. 4 is a frontal, top isometric view thereof;

FIG. 5 is a plan view thereof looking downwardly upon the device;

FIG. 6 is a left side elevational view thereof;

FIG. 7 is a front elevational view thereof, taken from a position generally to the left of FIG. 6;

FIG. 8 is a rear elevational view thereof, taken from a position generally to the right of FIG. 6;

FIG. 9 is a bottom plan view thereof; and,

FIG. 10 is a right side elevational view thereof, showing the side opposite that seen in FIG. 6.
